(57) **CLAIM**

The ornamental designs for a handle for a striking tool, as shown and described.

DESCRIPTION

FIG. 1 is a front perspective view of a first embodiment of a handle for a striking tool showing our new design;

FIG. 2 is a front elevational view thereof;

FIG. 3 is a back elevational view thereof;

FIG. 4 is a left side elevational view thereof;

FIG. 5 is a right-side elevational view thereof;

FIG. 6 is a top plan view thereof; and,

FIG. 7 is a bottom plan view thereof.

The broken line showings of the head are for illustrative purposes only and form no part of the claimed design.
